CIRCULAR KNITTING MACHINE

Alfred Woodward Kent, Groby, and Henry Harold Holmes, Leicester, England, assignors to Wildt and Company Limited, Leicester, England, a British company

Application April 8, 1937, Serial No. 135,780
In Great Britain April 16, 1938

7 Claims. (Cl. 66—14)

This invention relates to circular knitting machines and has particular reference to circular knitting machines of the double axially opposed needle cylinder type having independent latch 5 needles.

The object of the invention is to provide, in a circular knitting machine of this type, means of a simple character for casting stitches off needles and subsequently opening the latches of the same 10 needles, the purpose of this being, of course, to enable such needles to resume knitting at once when required.

The invention is intended for application more especially to machines of the type aforesaid which 15 include superimposed needle cylinders and double-ended latch needles as disclosed in British specifications Nos. 15,008 of 1900 and 24,290 of 1912.

The invention is applicable to both single and 20 multi-feed knitting machines, and to machines of the stationary needle cylinder type as well as to those of the revolving needle cylinder type.

Accordingly the invention consists of the provision of means (hereinafter referred to as the 25 casting off means) adapted to cause needles to cast off after knitting at the feed, or at one or more than one feed as the case may be, and to return such needles to a normal position preparatory to knitting again, and in combination with 30 the casting-off means latch opening means arranged so as to co-operate with the said needles when they are being restored to the normal position to effect the opening of the latches.

By the expression "normal position" is meant 35 any position to which the needles may be moved after knitting at the feed or any feed to enable them to knit again in the ordinary way.

In the accompanying drawings,

Figure 1 is a view drawn diagrammatically 40 and showing parts of two adjoining articles of a string of articles knitted in accordance with the invention.

Figure 2 is a view representing a development 45 of so much of the two cam systems at one feed of a machine of the superposed rotary needle cylinder type as is necessary to illustrate one embodiment of the invention.

Figure 3 is a detail sectional view taken on the 50 line III—III of Figure 2 and showing more clearly one of the cams of the casting-off cam arrangement shown in that figure.

Figure 4 is an elevational view of some of the 55 parts shown in Figure 3 as viewed from the outside of the machine.

Figure 5 is a detail perspective view hereinafter to be described.

Figures 6, 7 and 8 are detail plan views illustrating the operation of the cam shown in Figures 3 and 4.

Figure 9 is a side elevational view partly in section showing more clearly the latch opening means which are employed in conjunction with the casting-off cam arrangement.

Figure 9a is a detail view hereinafter to be 10 described.

Figure 10 is another view of the same as viewed from the outside of the machine.

Figure 11 is a view similar to Figure 2 (but showing only part of a bottom cam system) illustrating another embodiment of the invention.

Figure 12 is a detail sectional view taken on the line XII—XII of Figure 11.

Figures 13 and 13a are elevational views illustrating the means which are employed to operate 20 certain of the cams of the casting-off cam arrangement shown in Figure 11 as will be herein-after described, and

Figures 14, 15 and 16 are detail views illustrating the manner in which the said means 25 operate.

Like parts are designated by similar reference characters throughout the drawings.

In Figure 1, 1 represents the lower end and 2 the top of two adjoining articles, i. e. hose, half- 30 hose, three-quarter hose or socks, produced in string formation. At 3 are shown a few courses of plain knitting which, as will be seen, are interposed between the toe pouch 4 and a few courses of rib knitting 5 in the same article. An anti-run welt 6 is provided at the lower extremity of this article and between this welt and a welt 7 which precedes the rib top 8 of the next article there are a few parting or separating courses 9 of plain knitted loops. The courses 9, the purpose of which is to facilitate separation of the articles after knitting, can be effectively produced by employing in a machine of the superimposed rotary needle cylinder type either of the combined casting-off cam arrangements and latch 45 opening means now to be described.

According to the particular embodiment illustrated in Figures 2—10, there is provided in the bottom cam box 10 of the machine just beyond the knitting location x—in the direction of rotation of the needles, i. e. the direction indicated by the arrow A in Figure 2—a casting off cam arrangement comprising a fixed cam 11 for action upon slider knitting butts such as 12 (Figures 3, 6 and 7) so as to lower the corresponding sliders 55

and needles to a casting-off level C, an auxiliary lowering cam 13 for directing the said butts into engagement with the fixed cam 11, and, adjacent the latter, a fixed slider raising cam 14 for assisting in restoring the sliders and corresponding needles to the normal—in this example clearing—position as they next approach the knitting location, or the next knitting location, as the case may be. A fixed guard cam 15 is provided in association with the two casting-off cams. The auxiliary cam 13 is arranged for movement to and from the operative position indicated in Figure 6 and according to its position it determines whether or not the slider knitting butts 12 shall engage the casting-off cam 11 and consequently whether or not the corresponding needles shall be caused to cast-off. The cam 13 is arranged so that when operative it engages the slider knitting butts 12 at the clearing height D, the sliders being raised to this height after leaving the stitch cam 16 by means of a clearing cam 17 in order to clear the corresponding needles and enable them to cast off.

It is convenient to mention here that a welt track 18 is provided in the bottom cam system of the machine, this track having at the entrance thereto a radially movable cam 19 for opening and closing the track at the appropriate times. Normally the cam 19 is in to close the track 18. At those times when it is desired to form a welt, however, the said cam is withdrawn to open the track and those sliders having butts which are to enter the track must, of course, be prevented from being raised to clearing height after leaving the stitch cam 16 to enable the corresponding needle to retain their loops. For this latter purpose the clearing cam 17 is made vertically movable so that it can be moved, i. e. lowered, at the appropriate times from the normal clearing position indicated in full lines in Figure 2 to the position indicated in dot-and-dash lines in that figure. When the cam 19 is in to close the track 18 it serves as a raise cam to assist in restoring to the clearing position those sliders and corresponding needles which are lowered by the fixed casting-off cam 11.

The auxiliary cam 13 is of the radially movable bolt type and the bolt thereof is adapted to slide in the bifurcated upper part of a bracket 20 which is conveniently formed with ears or lugs 21 by means of which it can be secured by screws to the bottom cam box 10. The bolt of the cam 13 is retained in position by means of a plate 22 attached by means of screws 23 to the top of the bracket 20 and the underside of said bolt is recessed at 24 to accommodate the head 25 of a vertically disposed spindle 26. This spindle is mounted so as to be capable of a turning movement in a boss 27 formed on the bracket 20 and at its lower end has rigidly secured thereto a lever 28 by means of which the spindle can be turned. The lever is adapted to be controlled from the existing timing gear of the machine or some other control gear by intermediate connections (not shown). The head 25 is shaped in the manner shown more clearly in Figure 5 and has a flat face 29, which, when the cam 13 is in, i. e. operative, abuts against the rear face of the recess 24 (see Figures 3 and 6). The cam 13 has associated therewith a tension spring 30 which tends to move it into the operative position. One end of this spring is connected to the bolt of the cam and the other end to the plate 22 aforesaid. Thus by turning the spindle 26 so that the head 25 is turned from the position in-

dictated in Figure 6 into the position indicated in Figure 8, the cam 13 can be withdrawn against the action of the spring 30 from an operative into an inoperative position. Now normally the spindle 26 is held so that the head 25 is in the position shown in Figure 8. That is to say the cam 13 is normally held withdrawn, and is consequently inactive. At the appropriate time (determined by the control gear) the lever 28 is turned to bring the head into the position indicated in Figure 7 with the result that the cam 13 is allowed to spring half-way in. When in this position the said cam is close to the short butts 31 of the heel and toe series of sliders but does not act on these butts so that the sliders pass the cam 15 at clearing height. The cam is permitted to move half-way in when it is being approached by the instep series of sliders, and is held in this position for the appropriate interval of time by reason of a chamfered part 32 on the head 25 abutting against the rear face of the recess 24. Immediately the first long knitting butt 12' of the instep series of sliders engages the cam 13, the spindle 26 is simultaneously turned to bring the head 25 into the position indicated in Figure 6 and the said cam is consequently permitted to spring into its fully operative position in which it causes the butts 12 of the instep sliders to follow the path indicated by small arrows in Figure 2 with the result that the corresponding needles cast-off. Thus casting-off commences on the first instep needle and can be initiated on this same needle every time. Casting-off is terminated by the reverse action of the auxiliary cam 13.

The latch opening means for use in conjunction with the particular form of casting off means just described may be of any of the forms hereinbefore specified.

As shown more clearly in Figure 9, a latch opening cam member 33 shaped to provide a knife edge 34 to be presented to the needles such as 35 between the spoons of the closed latches 36 and the needle hooks 37, is located at a suitable point above the fixed raising cam 14. When the needles are raised by the said cam after casting off the knife edge 34 enters the slight angular recess 100 (Figure 9a) formed by the end of the closed latch and the receding curve of the needle hook which by reason of the continued rise of the needles pass respectively in front of and behind the said edge, so that the latches are opened. The slope on the cam 14 is gradual so as not to raise the needles too abruptly into engagement with the knife edge 34. The cam member 33 consists of a small block recessed as at 38 and thinned down within the recess to provide the knife edge, and is mounted on the top cam box 39 of the machine at the appropriate height and in the appropriate position circumferentially in relation to the knitting position. This block is secured, for example by means of screws, to the lower end of a lever 40 which is pivotally mounted between its opposite ends on a pivot pin 41 suitably carried by a small bracket 42 attached to the top cam box. The cam member 33 is capable of yielding for the purpose herein alluded to by reason of the interposition of a compression spring 43 between the upper end of the lever 40 and the adjacent part of the bracket 42. To provide for accurate setting of the knife edge 34 in relation to the needle latches there is conveniently provided an adjusting screw 44 which is screwed into the lever 40 and adapted at its free end to abut against a downwardly extending 75

projection or similar part, such as 45, formed or provided on the bracket 42. A lock nut 46 is provided to set the screw 45 in any position to which it is adjusted.

5 The embodiment of the invention illustrated in Figures 11-16 will now be described. According to this embodiment, which in many respects is similar to the embodiment just described, there is provided in the bottom cam box 47 of 10 the machine just beyond the knitting location x a casting off cam arrangement comprising a fixed cast-off cam 48 for action upon the slider knitting butts indicated at 49 (Figures 11 and 12) so as to lower the sliders and corresponding 15 needles to a casting off level C, an auxiliary lowering cam 50 for directing the said butts into engagement with the fixed cam, and at a suitable distance circumferentially from the fixed cast-off cam 48 a fixed slider raising cam 51 for re- 20 storing the sliders and corresponding needles to clearing position, as they next approach the knitting location or the next knitting location, as the case may be. Between the cams 48 and 25 51, guard cams such as 52 and 53 are conveniently provided to form a more or less horizontal path or track 54 for slider knitting butts to maintain the appropriate sliders in the casting off position. Other guard cams such as 55 and 30 56 may be provided in association with the slider lowering and raising cams. As in the previously described embodiment, the auxiliary cam 50 in the present embodiment is arranged for movement to and from an operative position, and according to its position it determines whether 35 the slider knitting butts 49 shall engage the casting off cam 48 or not and consequently whether the corresponding needles shall be caused to cast off or not. The operative position of the said cam is indicated in dot-and-dash lines in Figure 40 12 and when operative it engages the slider knitting butts 49 at the clearing height D, the sliders being raised to this height by an inclined part 57 of the cam 55 after leaving the stitch cam 58 in order to clear the corresponding needles and enable them to cast off. The auxiliary 45 cam 50 may be either pivotally or slidably arranged for movement into and out of this position and for this purpose is controlled from the existing timing gear of the machine by intermediate levers and linkage of any suitable character. In the specific example illustrated the 50 said cam is of the radially movable bolt type and is engaged with a spring controlled lever 59 adapted in turn to be acted upon by a bolt 60 55 connected by means of a link 61 with a main operating lever 62 arranged in engagement with a gapped cam ring 63 on a control drum or disc 64 on the main control shaft 65 of the machine. The bolt portion 50' of the cam 50 is slidably 60 mounted in a suitably drilled out part of a carrier block 66 which may be mounted either on the bed of the machine, or, as shown, on the flange 67 of the bottom cam box. The block 66 is slotted as at 68 for reception of the lever 59 65 and the latter is pivoted between its ends on a pivot pin 69 which extends transversely through the block. Near its upper end the lever 59 is enlarged and works in a recess 70 formed in the bolt 50', whilst at its lower end the said lever 70 is yieldingly held against the inner face of the bolt 60 by means of a tension spring 71 connected at one end to the lever and at the other end to the block 66. The bolt 60 is recessed as at 72 on its inner face. The arrangement so far de- 75 scribed is therefore such that so long as the

lower end of the lever 59 is held forward by the bolt 60 as indicated in Figures 12 and 14 the upper end of the lever maintains the cam 50 withdrawn, i. e. out, against the action of the spring 71. If now the bolt 60 is caused to move to the left (as viewed in Figures 13 and 14) the lower end of the lever 59 is allowed to drop into the recess 72 with the result that the cam 50 springs into the operative position indicated in dot-and-dash lines in Figure 12, i. e. it moves 10 in. The timing of the cam into operation is such that it engages the first long knitting butt 49 of the instep series of sliders, as will be hereinafter more fully explained.

15 At one end the link 61 aforesaid is adjustably connected to the bolt 60 by means of a bifurcated coupling member 73 and at the other end is conveniently attached to the upper end of the main operating lever 62. This lever is pivoted at 74 on any suitable part of the machine frame 20 and at its lower end is held in contact with the cam ring 63 by means of a tension spring 75. The gap in the ring is indicated at 76 and is of the form shown so that the lower end of the lever 62 at the appropriate times can drop to 25 the bottom of the gap and subsequently be raised to its normal position in two steps. The control drum or disc 64 is racked round in a clockwise direction. Thus while the gap 76 moves step by step past the lower end of the lever 62 the latter first moves from its normal position E 30 to position F and then from position F to position G prior to being moved again to the normal position. These movements are transmitted to the bolt 60 which first moves to the left from 35 its normal position (Figure 14) to the position indicated in Figure 15 and then moves to the right into the position indicated in Figure 16 prior to being restored to its normal position.

40 It is advantageous to provide in association with the auxiliary lowering cam 50 a movable auxiliary slider raising cam 77 for nullifying the casting off action without necessarily withdrawing the auxiliary lowering cam 50 at any particular time. This cam 77 which is of the same 45 form as the cam 50 is located immediately adjacent to the latter and when operative acts upon the slider knitting butts immediately after the lowering cam. The auxiliary raising cam 77 is adapted to be operated by a spring controlled lever 78 which is conveniently controlled by the same means as the lever 59 so that the cam 77 can be put into action without necessarily affecting the auxiliary lowering cam 50 50 which can be withdrawn subsequently. The cam 77 is timed to go into action so as to enable it to engage the first of the aforesaid series of long knitting butts with the result that the casting off can be commenced and terminated on the same needles notwithstanding the fact that 55 it may occur for more than one course. The lever 78 is accommodated in a slot 79 in the carrier block 66 and is controlled by a tension spring 80 (see Figure 13).

60 The operation of the mechanism just described 65 is as follows. For normal knitting the bolt 60 is held in the position indicated in Figure 14, in which position the lower end of the lever 59 is held forward whilst the corresponding end of the lever 78 is seated in the bottom of the recess 70 79. Consequently during normal knitting the cam 50 is out and the cam 77 is in. The bolt 60 is held in this position for as long as the lever 62 remains in the position E. At the commencement of casting-off the lever 62 is caused to 75

move to the position F with the result that the lower end of the lever 58 drops into the recess 72 and the corresponding end of the lever 78 is held forward. Thus the cam 58 moves in and the cam 77 is withdrawn and the timing of the cam 58 into operation is such that it engages the first long knitting butt of the instep series of sliders. Thus casting off can be initiated on the same needle. While the short butt sliders 10 are being lowered by the cam 58, the lever 62 is moved into the position G and consequently the cam 58 still remains in but the recess 72 is brought opposite to the lower end of the lever 78. In these circumstances the cam 77 will be prevented 15 by the short butts from moving in until the last short butt has passed it. Simultaneously with the passing of the said last butt, however, the cam 77 moves in and thus nullifies or terminates the casting off action without there being any 20 necessity for immediately withdrawing the lowering cam 58. This withdrawal of the cam 58 is effected as the result of the subsequent return of the lever 62 to the normal position E.

The latch opening means for use in conjunction with this form of casting-off means are conveniently the same as those employed in the previously described embodiment of the invention.

For producing articles such as those shown in Figure 1 in string formation on a circular knitting machine of the superimposed needle cylinder type the latter is operated to produce plain knitting for one or more courses after knitting one article, e. g. after knitting a toe such as 4 25 of a hose, half-hose or like article, after which a transfer is made to rib knitting and then knitting is suspended on one set of needles for two or more courses to form an anti-run welt. Rib knitting is then resumed and the casting off 30 mechanism is put into operation to cause the plain needles to cast off their stitches to form a parting or separating courses of rib loops, the latch opening means function as aforesaid to open the needle latches of the bare needles before these reach the knitting position again. The casting off action may continue for a complete 35 course or more—according to the arrangement and timing adopted, following which the casting off mechanism is rendered ineffective and two or three needles later (approximately) the welt cam is withdrawn for the purpose of making the welt of the next article, and when a welt of the required number of courses has been made rib knitting may be resumed; for example if a rib top or the like is required.

Other latch opening means which may be adopted are (a) a point arranged, for example obliquely disposed, to come between the latch and hook of any needle restored to normal position after casting off so as to open the latch by reason of the movement of the needle in relation to the point; (b) a brush arranged to act upon the latches of any needles previously caused to cast off when such needles resume the normal position; (c) a revolving brush driven from the needles, or independently by small gears or in any other convenient manner, and arranged to work upon the latches of any needles moving back from the casting off position as aforesaid, or 45 (d) a revolving member fitted with a circular series of latch opening elements which may be arranged on the inside of the needle circle and be individually movable by cam means for causing said elements to co-operate with individual 50 needles, when needles previously caused to cast

off move back to the normal position preparatory to knitting again. The said revolving member may be driven from the needles or independently like the brush.

As regards latch opening this may be facilitated by vibrating the needles vertically or sideways. For example and as shown in Figure 11, a step 81 may be formed in the casting off path or track 84 so as to impart a slight abrupt upward movement to the needles with that end in 10 view.

If desired, means may be provided for controlling the needles which have cast off as such needles approach the latch opening means so that they are in a favourable position to be acted 15 upon effectively by the latch opening means. According to one arrangement advantageously employed in conjunction with a knife edge cam member, a cam or cam surface is provided in advance of the latch opening means for action 20 upon the hooks or heads of the empty needles for the purpose of pressing and holding them back in their tricks. For example the cam surface may be provided on the back of the aforesaid small block in advance of the recess. This 25 is especially useful in a machine of the rotary needle cylinder type for the purpose of counteracting any tendency of the empty needles to move outwards in their tricks under centrifugal force.

In applying the invention to a revolving cylinder machine having two or more feeders a corresponding number of casting-off mechanisms and latch opening means may, of course, be provided, according to requirements.

What we claim then is:

1. In a circular knitting machine, superposed rotary needle cylinders, double-ended latch needles in said cylinders, needle operating sliders for transferring needles from one cylinder to the other, said sliders having thereon knitting butts, a cam box associated with each cylinder and having therein cams for action on slider knitting butts, a casting-off cam arrangement which is provided in the bottom cam box beyond a knitting location, said cam arrangement including a fixed cam for action upon slider knitting butts so as to lower the sliders and corresponding needles to a casting-off level and a fixed slider raising cam for restoring sliders and corresponding needles to the normal position as they next approach the knitting location, and latch opening means for co-operating with the said needles when they are being restored to the normal position to effect the opening of the corresponding latches.

2. In a circular multi-feed knitting machine, superposed rotary needle cylinders, double-ended latch needles in said cylinders, needle operating sliders for transferring needles from one cylinder to the other, said sliders having thereon knitting butts, a cam box associated with each cylinder and having therein cams for action on slider knitting butts, a casting-off cam arrangement which is provided in the bottom cam box beyond each of more than one knitting location, said cam arrangement including a fixed cam for action upon slider knitting butts so as to lower the sliders and corresponding needles to a casting-off level and a fixed slider raising cam for restoring sliders and corresponding needles to the normal position as they next approach the appropriate knitting location, and latch opening means for co-operating with the said needles when they are being restored to the normal position to effect the opening of the corresponding latches.

3. In a circular knitting machine, superposed rotary needle cylinders, double-ended latch needles in said cylinders, needle operating sliders for transferring needles from one cylinder to the other, said sliders having thereon knitting butts, a cam box associated with each cylinder and having therein cams for action on slider knitting butts, a casting-off cam arrangement which is provided in the bottom cam box beyond a knitting location, said cam arrangement comprising a fixed cam for action upon slider knitting butts so as to lower the sliders and corresponding needles to a casting-off level, an auxiliary lowering cam for directing said butts into engagement with the fixed cam, said auxiliary cam being arranged for movement to and from an operative position, and a fixed slider raising cam for restoring sliders and corresponding needles to the normal position as they next approach the knitting location, and latch opening means for co-operating with the said needles when they are being restored to the normal position to effect the opening of the corresponding latches.
4. A combination according to claim 3, wherein there is provided in association with the auxiliary lowering cam a movable auxiliary slider raising cam, for the purpose herein described.
5. In a circular knitting machine, superposed rotary needle cylinders, double-ended latch needles in said cylinders, needle operating sliders for transferring needles from one cylinder to the other, said sliders having thereon knitting butts, a cam box associated with each cylinder and having therein cams for action on slider knitting butts, a casting-off cam arrangement which is provided in the bottom cam box beyond a knitting location, said cam arrangement including a fixed cam for action upon slider knitting butts so as to lower the sliders and corresponding needles to a casting-off level and a fixed slider raising cam for restoring sliders and corresponding needles to the normal position as they next approach the knitting location, and a cam member shaped to provide a knife edge to be presented to the said needles between the spoons of the closed latches and the needle hooks when the needles are being restored to the normal position, for the purpose of opening said latches.
6. In a circular knitting machine, in combination, axially opposed needle cylinders, independent latch needles having needle hooks and closed latches in said cylinders, a cam box associated with each cylinder and having therein cams for effecting the movements of the needles, a casting-off cam arrangement which is provided in one of said cam boxes beyond a knitting location, said cam arrangement including a cam for effecting a lowering movement of needles to a casting-off level and a cam for restoring needles to the normal position as they next approach the knitting location, and a cam member which is arranged above the needle path and has a vertical rear face and a rearwardly sloping face intersecting said rear face so as to provide a downwardly facing knife edge to be presented to the upper ends of said needles between the spoons of said closed latches and said needle hooks when the needles are being raised to the aforesaid normal position to open said latches.
7. In a circular knitting machine, axially opposed needle cylinders, double-ended latch needles in said cylinders, needle operating sliders for transferring needles from one cylinder to the other, said sliders having thereon knitting butts, a cam box associated with each cylinder and having therein cams for action on said slider knitting butts, a casting-off cam arrangement which is provided in one of the cam boxes beyond a knitting location, said cam arrangement including a cam for action upon said slider knitting butts and operative to lower the sliders and corresponding needles to a casting-off level and a slider raising cam operative to raise said sliders and corresponding needles to the normal position as they next approach the knitting location, and latch opening means positioned above the needle path, and said slider raising cam bringing said latches into contact with said latch opening means when said needles are being raised to be restored to the normal position to effect the opening of the corresponding latches.

ALFRED WOODWARD KENT.
HENRY HAROLD HOLMES.
